ATTORNEY.

UNITED STATES PATENT OFFICE.

FREDERICK GRILL, OF PHILADELPHIA, PENNSYLVANIA.

DEVICE FOR SECURING CUT TOBACCO.

SPECIFICATION forming part of Letters Patent No. 380,256, dated March 27, 1888.

Application filed October 10, 1887. Serial No. 251,898. (No model.)

To all whom it may concern:

Be it known that I, FREDERICK GRILL, a citizen of the United States, residing in the city and county of Philadelphia, State of Pennsylvania, have invented a new and useful Improvement in Devices for Securing Cut Tobacco, which improvement is fully set forth in the following specification and accompanying drawings.

10 My invention consists of means for packing cut tobacco, whereby the tobacco may be examined and the quality of the same readily determined, while avoiding foil, paper, and other wrappings and preserving the flavor and 15 moisture of the tobacco, other advantages being possessed, as will be hereinafter fully set forth.

Figure 1 represents a side elevation of a package of fine-cut tobacco embodying my invention. The remaining figures (seventeen) represent modifications of tags that may be employed.

Similar letters of reference indicate corresponding parts in the several figures.

25 In the drawings, A represents a package of fine-cut tobacco, which may be of any shape, and B represents a fastener therefor, the same being formed of a piece of wire, or cord, if preferred, having its ends connected, forming a 30 loop which is twisted or bent at the center, producing a neck or link, C, thereat, and a double loop or two loops, D D. When the wire is bent to form the neck or link, the latter may be preserved by a piece of wire, soldering, &c.

In Fig. 18 I show two loops which are connected as links and have their places of contact constitute a neck, C, said figure being on a reduced scale.

40 The package A is placed within the loops D D, the neck C being below, and the upper ends of the loops are brought together and secured by a tag, E, whereby the loops are prevented from separation, and the tobacco 45 is nicely retained within the loops, owing to the spreading nature of the loops from the neck to the place of fastening, it being seen that the surface of the package is almost entirely exposed, as the loops are of skeleton

form and sink somewhat into the tobacco and 50 are concealed therein, by which provision the tobacco may be examined by the purchaser and its quality and condition determined, rapid drying and deterioration being avoided, unlike tobacco which is packed in closed wrappings 55 of foil, paper, &c.

The packages may be readily placed in boxes, and the tobacco while therein may also be examined or inspected and its character and condition determined. 60

The face-plate E' of the tag E admits of placing the brand, manufacturer's name, and other information thereon, and the tag may be variously constructed.

In Fig. 1 the tag has a single pin, F, which 65 passes through the overlapped ends of the tops of the two loops. In Fig. 2 the tag has two pins, which may enter the ends of the two loops, the pins in either case piercing the tobacco. In Figs. 3 and 4 eyes F are employed 70 for connecting the tops of the loops. In Fig. 5 two pins, F, are connected with the tag and adapted for engagement with the loops. In Fig. 6 there are two elastic fingers, F, which enter the tops of the loops. Fig. 7 shows a 75 spring-pin, F, attached to the plate E'. Fig. 8 has upturned eyes attached to the plate. Fig. 9 represents a plate with eye portions E' 80 integral therewith. Fig. 12 represents a section on line z z, Fig. 9, the eye portions E' being bent down, forming eyes or loops F. In Fig. 10 two plates are shown, one having pins which tightly enter sockets on the other plate, the loops being placed between the plates. Figs. 13, 14, 15, and 17 illustrate two 85 plates pivoted together and adapted to receive the tops of the loops between them, Fig. 15 being a section on line y y, Fig. 13, and Fig. 17 a section on line z z, Fig. 14. Fig. 11 represents the top of one loop passed through 90 eyes in the face-plate of the tag, the top of the other loop being caught beneath said plate, Fig. 16 being a section on line a a in said Fig. 11.

Having thus described my invention, what I 95 claim as new, and desire to secure by Letters Patent, is—

1. A fastener for tobacco, consisting of a

two-part loop with a neck joining the parts thereof, and a device for securing the opposing ends of said parts, substantially as described.

2. A fastener for tobacco, consisting of a double loop with a connecting link or neck and a locking-tag, substantially as described.

3. A fastener for tobacco of skeleton form,

consisting of a loop with a link or neck integral therewith, and a device for locking the ends of said loop, substantially as described. 10

FREDERICK GRILL.
